(57) **CLAIM**

The ornamental design for a chair, as shown and described.

DESCRIPTION

FIG. 1 is a perspective view of a chair showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial, enlarged view of the portion taken at line-9 in FIG. 1; and,

FIG. 10 is a partial, enlarged view of the portion taken at line-10 in FIG. 1.

The broken lines in the figures are for the purpose of illustrating portions of the chair, which form no part of the claimed design.

1 Claim, 10 Drawing Sheets(56)
